UNITED STATES PATENT OFFICE.

ALBERT H. TAYLOR AND LEO C. YOUNG, OF WASHINGTON, DISTRICT OF COLUMBIA,
ASSIGNORS TO WIRED RADIO, INC., OF NEW YORK, N. Y., A CORPORATION OF DELA-
WARE.

MODULATION SYSTEM FOR FREQUENCY MULTIPLIER CIRCUITS.

Application filed August 6, 1925. Serial No. 48,612.

Our invention relates broadly to electron tube systems and more particularly to a method of modulating an electron tube system for electrical signaling.

5 One of the objects of our invention is to provide a method of modulating an electron tube system, where the frequency of a local oscillator is multiplied and then the amplitude of the oscillations at the multiplied frequency increased for operation of the signaling system.

10 Still another object of our invention is to provide a system of modulating a frequency multiplier tube circuit in an electron tube system for the production of signals wherein modulation is effected by variation in the grid voltage of the frequency multiplying tube.

15 A further object of our invention is to provide a modulation system in an electron tube circuit arrangement employing a frequency multiplier tube, where a minimum amount of apparatus is required for effecting modulation.

20 25 A still further object of our invention is to provide a system of electron tubes coupled one to another where one of the tubes is employed for the production of high frequency oscillations and an adjacent tube utilized as a frequency multiplier and the next adjacent tube utilized as a power amplifier where modulation becomes dependent upon the negative potential of the grid of the frequency multiplier tube, whereby small variations in the input circuit current of the frequency multiplier tube may be employed to effect large fluctuations in the energy of the harmonic developed by the frequency multiplier.

30 35 40 Our invention relates more specifically to an electron tube system which is described more particularly in a co-pending application for Letters Patent filed by A. Hoyt Taylor, S. N. 48,611, filed August 6, 1925. The improvement described herein is directed to a method of modulating the circuit arrangement or system described in the said co-pending application.

45 Our invention will be more clearly understood by reference to the following specification and the accompanying drawing, which shows diagrammatically the arrangement of the electron tubes in the signaling system and the modulation circuit in connection with the

input circuit of the frequency multiplier tube.

We have illustrated our invention with particular reference to an electron tube radio transmission system, but we desire that it be understood that the principles of the invention may be applied to an electron tube system which is utilized for any purpose, such as the impression of high frequency signaling energy upon a line wire system. The arrangement we have illustrated is equally applicable to the modulation of high frequency currents in wired radio transmission systems and it will be understood that the connections which we have shown to the antenna ground system may be substituted for connections leading to a line wire system. We have discovered that in a frequency multiplier tube circuit to which is coupled the output of an electron tube oscillator, that the production of harmonic frequencies and the doubling or increase of frequency is directly dependent upon the voltage impressed across the grid and filament electrodes and the negative biasing of the grid. The grid circuit of the frequency multiplier tube requires very small current variations for the production of large fluctuations in the energy of the harmonic frequency which is derived from the fundamental frequency. We, therefore, provide in the input circuit of the frequency multiplier tube a speech frequency transformer, the primary winding of which is connected to a microphone or other source of variable current. By varying the negative biasing on the grid of the frequency multiplier tube in accordance with speech vibrations modulation of the harmonic frequency may be produced. The modulated harmonic frequency is impressed upon a circuit tuned to such harmonic and the energy then transferred to the input circuit of a power amplifier by which it is increased in amplitude and conveyed to the signaling system.

50 55 60 65 70 75 80 85 90 95 100 105 Referring more particularly to the accompanying drawings reference character 1 designates an electron tube arranged as an oscillator with the frequency thereof controlled by means of piezo electric crystal 2 connected in the input circuit of the oscillator in series with booster choke 3. A negative potential is impressed upon the grid electrode 1^a of tube 1 from the source 4

through high frequency choke 5. The power input circuit of the tube 1 from plate electrode 1^b is completed through radio frequency choke 6 to the high potential supply system 7 across which the potentiometer 8 may be placed with an adjustable contact 9 for securing the proper value of plate potential for the several tubes of the system. Electron tubes 10 and 11 are arranged in the signaling circuit with the grid, filament and plate electrodes thereof connected in the input and output circuits of each of the tubes with the input and output circuits interconnected with the output circuit of one of said tubes coupled with the input circuit of a succeeding tube. The filaments 1^c, 10^c and 11^c of each of the tubes are supplied from source 12, the incandescence of each filament electrode being controllable through rheostats 14, 15 and 16. The oscillator tube 1 has a tuned output circuit 17 comprising variable condenser 18 and inductance 19. The input circuit of the tube 10 is connected with the tuned output circuit 20 of the tube 1. The tube 10 has a tuned circuit 20 connected in its output circuit, the tuned circuit consisting of variable condenser 21 and inductance 22 with the tuned circuit 20 next to the input circuit of the power amplifier tube 11, the output circuit of which connects to any desired form of work circuit. We have illustrated the signaling system as applied to a radio telephone circuit where the output energy from the power amplifier tube 11 is impressed upon an antenna ground circuit 23—24 through coupling inductances 25 and 26. We provide plate feed condensers 27, 28 and 29 in the output circuits of the several tubes. Radio frequency choke coils 6, 30 and 31 are placed in each of the plate circuits of the several tubes. A high potential source 32 is provided which is tapped at 33 and 34 to the input circuits of tubes 10 and 11 respectively. In order to develop harmonic oscillations in the circuits interconnecting the electrodes of tube 10 of a frequency higher than the frequency of the oscillations developed in tube 1, the grid electrode 10^a is overexcited with a relatively high negative potential. Radio frequency choke coils 35 and 36 are disposed in each of the biasing circuits. A coupling transformer 37 is disposed in the input circuit of tube 10 with the primary winding 38 thereof connected to source 39 and to microphone 40. The secondary winding 41 of the modulation transformer 37 is connected directly in the biasing circuit leading to the grid electrode 10^a. Where necessary we may interpose a voice amplification system in the modulation circuit leading to the primary winding 38 of the coupling transformer. In this manner the signaling currents may be employed to vary the value of negative potential on the

grid of the frequency multiplier tube 10 as a result of which the oscillations of increased frequency are modulated and their amplification increased by means of the power amplifier tube 11. We provide balancing capacities 42 and 43 between the tube circuits for preventing reaction between the several tube circuits. One tube is prevented from reacting upon another and the modulation of oscillations which are multiplied in frequency through the frequency multiplier tube 10 effected. 70 75

While we have described our invention in a certain particular embodiment, we desire that it be understood that modifications may be made and that no limitations upon the invention are intended other than are imposed by the scope of the appended claims. 80

Having thus described our invention what we claim and desire to secure by Letters Patent of the United States is as follows: 85

1. In a signaling system the combination of a plurality of electron tubes each having input and output circuits, with the output circuit of one of said tubes interlinked with the input circuit of a succeeding tube, one of said tubes being arranged for the generation of high frequency oscillations, another of said tubes being arranged to multiply the frequency of said oscillations, and variable means connected to the input circuit of said last mentioned tube for modulating the oscillations of increased frequency thus developed. 90 95

2. In a signaling system the combination of a plurality of electron tubes each having input and output circuits, with the output circuit of one of said tubes interlinked with the input circuit of a succeeding tube, one of said tubes being arranged for the generation of high frequency oscillations, another of said tubes being arranged to multiply the frequency of said oscillations, means for impressing a relatively high negative potential upon the input circuit of said last mentioned tube and separate means for varying the value of said negative potential in said last mentioned input circuit for modulating the oscillations of increased frequency. 100 105 110

3. In a signaling system the combination of a plurality of electron tubes each having grid, filament and plate electrodes, input and output circuits interconnecting said electrodes, means interlinking the output circuit of one of said tubes with the input circuit of a succeeding tube, said first mentioned tube having means for the generation of high frequency oscillations, the next adjacent tube having means for multiplying the frequency of the oscillations thus developed and the next adjacent tube having means for increasing the amplitude of the oscillations thus developed, means for impressing a high negative potential upon the grid electrode of said second mentioned tube, and means for vary- 115 120 125 130

ing the value of said negative potential on said grid electrode for modulating the oscillations of increased frequency thus developed.

5 4. In a signaling system the combination of a plurality of electron tubes each having grid, filament and plate electrodes, input and output circuits interconnecting said electrodes, means interlinking the output circuit 10 of one of said tubes with the input circuit of a succeeding tube, said first mentioned tube having means for the generation of high frequency oscillations, the next adjacent tube having means for multiplying the frequency 15 of the oscillations thus developed and the next adjacent tube having means for increasing the amplitude of the oscillations thus developed, means for overexciting the grid electrode of said second mentioned tube by 20 impressing high negative bias thereon and separate means for varying the degree of overexcitation of said grid electrode in accordance with signals for modulating the amplitude of oscillations of increased frequency. 25

5. In a signaling system the combination

of a plurality of electron tubes each having grid, filament and plate electrodes, input and output circuits interlinking said electrodes, means interlinking the output circuit of one of said tubes with the input circuit of a succeeding tube, said first mentioned tube having means for the generation of high frequency oscillations, the next adjacent tube having means for multiplying the frequency of the oscillations thus developed, and the next adjacent tube having means for increasing the amplitude of the oscillations thus developed, a source of negative potential, circuit connections between said source and the grid electrode of said second mentioned tube, a coupling transformer disposed in said circuit connections, a modulation circuit connected with said coupling transformer for varying the value of negative potential impressed upon the grid electrode of 30 said second mentioned tube for varying the amplitude of the oscillations of increased frequency thus developed. 35
